UNITED STATES PATENT OFFICE.

WILLIAM H. DOWNING, OF GOODELL, PENNSYLVANIA.

SUCKER-ROD ADJUSTER.

SPECIFICATION forming part of Letters Patent No. 364,226, dated June 7, 1887.

Application filed August 3, 1886. Serial No. 209,861. (No model.)

To all whom it may concern:

Be it known that I, WILLIAM H. DOWNING, of Goodell, in the county of McKean and State of Pennsylvania, have invented certain new and useful Improvements in Sucker-Rod Adjusters; and I do hereby declare the following to be a full, clear, and exact description of the invention, such as will enable others skilled in the art to which it pertains to make and use it, reference being had to the accompanying drawing, which forms part of this specification.

My invention relates to an improvement in sucker-rod adjusters; and it consists in the combination of the trunnion, which is to be journaled upon one end of the walking-beam, the hollow screw or tube, which passes through the trunnion and which is adjustable endwise therein, the polish-rod, which passes through the hollow screw or sleeve, the collar, which is applied to its upper end above the top of the hollow screw, and the clamping-screw, which passes into the upper end of the collar or sleeve, all of which will be more fully described hereinafter.

25 The object of my invention is to produce an attachment for the sucker-rods of deep wells, and in which the rods cannot become unscrewed. The rods can be raised and lowered without using ropes or bull-wheels. The rods 30 can be turned and held in different positions to loosen the paraffine in the tube, so that it will pump out and so that the adjuster need not be taken off the beam to pull the rods out of the well.

35 The accompanying drawing represents a vertical section of an apparatus embodying my invention.

A represents one end of the walking-beam, and B the trunnion, which is pivoted thereon in the usual manner. The end of the walking-beam A is pronged or bifurcated, and upon the prongs are secured the boxes X, in which the trunnions B partially rotate. The inner ends of the trunnions B are secured to the collar or sleeve Y, which is provided with the wings Z, which are internally screw-threaded, so as to make connection with the trunnion, as shown. This collar is screw-threaded internally through its vertical portion, so as to receive 50 the sleeve C, which is screw-threaded externally, as shown. Passing vertically through

this collar Y is the hollow screw or sleeve C, of suitable length, and upon which is placed the lock-nut D, which is provided with a handle upon one side, for the purpose of locking 55 the screw or sleeve C in position, so that it cannot turn around in the collar while the pump is at work. To the upper end of this hollow screw or sleeve C is rigidly secured the perforated cap or cover F, which is provided with the handles G, and by means of which the sleeve or screw can be turned around for the purpose of adjusting it endwise through the trunnion B. Passing up through this hollow screw or sleeve 60 C is the polish-rod H, which has a screw-coupling upon its lower end, connecting with the pumping-rod, and which has a screw-threaded tenon, I, formed upon its upper end. The shoulder formed upon the upper end of this rod H acts as a stop to the rod, so that the tenon 65 I only will project through the rod or cap F. Screwed upon the thread of the tenon I is the sleeve J, which is provided with the handles L, so that the sleeve can be turned for the purpose of screwing it upon the tenon or removing 70 it therefrom at will. Screwed into the top of this sleeve J is the clamping-screw O, which has the ring P formed upon its upper end. After the collar J has been screwed upon the tenon I the screw O is forced down into the collar, so as 75 to bear against the tenon I, and thus prevent the tenon from turning and becoming loosened from the collar. This collar J supports the polish-rod in position in the hollow screw or sleeve C. By turning the screw or sleeve C it will be 80 adjusted vertically through the trunnion B, and this rod H will be raised and lowered at the will of the operator. After the screw-rods have been detached from the polish-rod H and 85 it is desired to remove the rod H, it is only necessary to remove the sleeve J, when the rod H can be detached entirely from the sleeve. By means of the construction here shown a single person can raise and lower the rods connected with the working valves in the well, without 90 having to use a rope or any of the tools heretofore employed for that purpose, by simply standing upon the walking-beam and then turning the hollow screw or sleeve C. In disconnecting the adjuster from the sucker-rods the 95 adjuster need not be taken off from the beam, and thus a saving of time and labor is effected.

The polish-rod being connected to the hollow screw or sleeve in the manner here shown, the rod cannot become unscrewed, so as to drop the valves together. The rods can also be 5 turned and held in different positions, so as to loosen the paraffine in the tubing, so that it can be pumped out.

Having thus described my invention, I claim—

10 1. The combination of the beam A, the boxes X, mounted thereon, the trunnions B, journaled in the boxes, and the internally-screw-threaded collar Y, connected to the trunnions at their inner ends, with the hollow screw rod or sleeve C, which is screw-threaded externally, as shown.

15 2. The combination of the beam A, the boxes X, mounted thereon, the trunnions B, journaled in the boxes, the internally-screw-threaded

collar Y, connected to the trunnions at their 20 inner ends, the hollow screw rod or sleeve C, the polish-rod H, which passes through the sleeve, and the sleeve J, which screws upon the upper end of the polish-rod above the sleeve C and supports it in position, substan- 25 tially as described.

3. The combination of the trunnion, the hollow screw rod or sleeve, the polish-rod, the sleeve that screws upon the upper end of the polish-rod, and the clamping-screw, substan- 30 tially as set forth.

In testimony whereof I affix my signature in presence of two witnesses.

WILLIAM H. DOWNING.
